UNITED STATES PATENT OFFICE.

MARTIN KOERT, OF PASSAIC, NEW JERSEY, ASSIGNOR TO SALVATION MATCH COMPANY, OF NEW YORK, N. Y., A CORPORATION OF NEW YORK.

MATCH-MACHINE.

1,145,200.

Specification of Letters Patent.

Patented July 6, 1915.

Application filed August 25, 1914. Serial No. 858,529.

To all whom it may concern:

Be it known that I, MARTIN KOERT, a citizen of the United States, residing at Passaic, Passaic county, New Jersey, have invented a new and useful Improvement in Match-Machines, of which the following is a full, clear, and exact description.

My invention relates to improvements in match machines and more particularly to the so called "station"; that is the mechanism by which the splints are separated from a mass and inserted in a carrier preparatory to dipping them in the paraffin and firing compositions. With machines of this type much difficulty has been had at this particular part of the machine because many of the splints are wasted and they are very likely to become more or less entangled and interfere with the proper working of the mechanism.

The object of my invention is to produce a very simple and efficient mechanism by which the splints can be inserted in the carrier and to arrange and construct this mechanism so that it can be easily reached, so that it can be easily adjusted to the end that the splints may always register with the parts of the carrier intended to receive them, and further to construct the apparatus so that the splints are practically certain to be inserted in the right relation and without clogging in the carrier.

A further object of my invention is to construct the guiding devices and combs of the plungers in such a manner that they may be instantly and easily adjusted to bring the plungers into correct alinement with the holes or corresponding parts of the carrier; to construct and arrange the shaker so that the splints are practically certain to be shaken into the guide comb in correct relation and to arrange the parts so that if any splint or splints become displaced it will not interfere with the working of the apparatus.

Reference is to be had to the accompanying drawings forming a part of this specification, in which similar reference characters indicate corresponding parts in all the views.

Figure 1 is a broken plan view of the structure embodying my invention showing the same in its correct relation with the carrier; Fig. 2 is a detail plan view of the shaker; Fig. 3 is a longitudinal section of

the shaker; Fig. 4 is a cross section on the line 4—4 of Fig. 1; and Fig. 5 is a section on the line 5—5 of Fig. 1.

The machine has a suitable frame 10 which is part of the general match machine 60 and extending across this frame is a plate 11, one portion of which, that is the part farthest from the carrier 16, hereinafter referred to, is slotted on its upper side to form a series of guideways 12, in which 65 slide the plungers 13, each plunger having preferably a reduced end portion 14 (see Fig. 5) on which a match splint may rest. These plungers 13 reciprocate horizontally in a line perpendicular to the carrier 16, which, 70 as illustrated, has holes 15 in which the splints are severally inserted.

The carrier 16 can be any approved form of carrier and in match machines it is customary to make this an endless carrier and 75 the splints, after being inserted, are carried forward and dipped in various compositions. The means of moving the carrier and of holding the splints is not pertinent, however, to my invention which relates 80 wholly to the means of placing the splints in the carrier. The carrier is usually driven by screws 17 on shafts 18 (see Figs. 1 and 4) but I have not shown the driving mechanism as it has nothing to do with this case. 85

The plungers 13 are arranged in parallel relation so as to aline with the splint holding parts of the carrier 16 and they have preferably a dove-tail connection as at 19 (see Fig. 5) with a cross head 20, which reciprocates in the machine frame and which at the sides and ends has rearwardly extending arms 21, carrying rollers 22, which enter the slotted ends 23 of the rocking arms 24, which are pivoted on a shaft 25, carried 95 by the main frame 10. The lower ends of the arms 24 merge in eccentric straps 25 on the eccentrics 26, which are carried by the shaft 27. Thus, it will be seen that the rotation of the eccentrics will rock the arms 100 24 and move the cross head 20 and plungers 13 backward and forward so that the plungers can carry forward the splints and insert them in the holes 15 of the carrier 16. In practice, this reciprocating mechanism is 105 timed so that the plungers will move forward with their splints when the carrier 16 is in a position to bring the hole 15 or corresponding parts into alinement with the plungers, but I have not shown this timing mech- 110

anism as it is common to all match machines of this type. It will be understood, too, that the particular means of reciprocating the plungers can be changed without in any 5 way affecting my present invention.

The plungers 13 have their splint carrying portions 14 moving through a guide comb formed by slotting the upper portion of part of the plate 11 to produce the teeth 10 or guides 28 which are preferably rounded 15 on their upper edges as shown at 28^a in Fig. 4, so that the splints which lie above them and which are moved back and forth by a shaker to be presently described, will fall readily between the teeth 28 so as to lie upon the parts 14 of the plungers. As the splints are carried forward by the plungers 13 they also move between parallel 20 guides 29 which are arranged near the carrier 16 and which are relatively high so that as the carrier moves forward the splints will be guided by these parts and prevented from tipping in a manner to bring their outer portions together. These guides 25 30 are carried by a plate 30 with which they are preferably integral, and this plate is attached to the plate 11 already referred to. The plungers 13 also slide beneath a cross bar 31 which is parallel with the plate or bar 30 (see Fig. 5) but is spaced apart therefrom so as to provide clearance for the splints as they drop from the shaker 39, hereinafter referred to, upon the plungers 13. The bar 31 serves to guide the shaker 35 and it also binds in place a hood 32 of sheet metal which extends across the top of the plungers and prevents any loose splints from dropping into the plungers or adjacent mechanism. The bar 31 also serves to prevent 40 the plungers 13 from being thrown upward by contact with any displaced splint.

The plungers 13 are inclined to wear slightly in the plate 11 and the carrier 16 is also inclined to stretch a little so that occasionally adjustment is necessary to bring the plungers 13 into proper alignment with the holes 15 or analogous parts of the carrier. It is often quite difficult to keep this adjustment absolutely perfect, which is essential to good work. To provide for this I support the plate 11 on vertically adjustable brackets 33 which are arranged on opposite sides of the machine frame 10 and are preferably in the form of channel irons. 55 These brackets are slotted vertically as shown at 34 in Fig. 5 and move on binding studs or screws 35. The brackets can be instantly adjusted vertically by means of the screws 36 which extend through the lower 60 parts of the brackets and also are threaded into the ledges 37 on the frame 10. Thus, it will be seen that by adjusting the screws 36 the plate 11 can be vertically adjusted and as this carries the guides for the plungers and also the plate 30 with the guides 65

29 it will be seen that the whole plunger guiding mechanism can be instantly and accurately adjusted.

The splints are held in mass above a shaker 39 in any suitable manner so that they will drop horizontally downward into the shaker. This shaker has a generally rectangular open frame which slides transversely on the bar 31 and plate or bar 30, having preferably a recess fitting a rib 38 on the cross plate or bar 30 to prevent any displacement of the shaker. The shaker is traversed at frequent intervals by vertically arranged cross plates 40 and 41, the latter being higher than the former and the several plates being spaced apart a distance less than the length of the match splint. Thus, as the shaker moves backward and forward it will shake the splints into parallel relation and into parallel relation with the plungers 13, while the higher cross plates 41 will cause the splints to tip down so that their ends will enter between two adjacent plates and thus prevent them from lying flatwise on the shaker top and clogging the feeding action of the machine. The shaker can be reciprocated in any suitable manner. I prefer the means shown in which the shaker, at one end, has a projecting bracket 42 and at the other a bracket 43. 90 The bracket 42 carries a roller 44 which runs on the face of a rotating cam wheel 45, which imparts motion to the shaker in one direction and it is held against the cam wheel by a spring 47 which connects with an adjusting screw 46 in the end of the bracket 43 and also with an abutment 48 which rises from the plate 11 while the movement of the shaker is limited by a similar abutment 48^a, rising from the opposite end of the plate 11. It will be seen that as the splints fall into the shaker they will be straightened out by the reciprocation of the latter and will fall between the teeth 28^a of the guide comb in position to lie upon the part 14 of the plungers 13. As the plungers move forward the splints which are thus brought into position will be carried forward beneath the bar 30 between the guides 29 and inserted in the holes 15 of the carrier 16. When the plungers are drawn back the carrier steps forward and a new series of splints fall upon the plungers ready to be inserted in the next set of holes.

From the foregoing description, it will be seen that I have devised a simple and very accurate splint inserting mechanism for a match machine, and I have found in actual shop use that this works in a very satisfactory manner with little loss of splints and with possibilities of quick and accurate adjustment.

I claim:

1. In a match machine, the combination with the splint carrier and the reciprocating

plungers, of guides for the plungers, guiding mechanism for the splints parallel with the plunger guides and nearer the carrier, and means for simultaneously adjusting the 5 plunger and splint guiding mechanism.

2. In a match machine, the combination with the reciprocating plungers, the splint carrier, and guides for the plungers, of means for simultaneously adjusting the 10 plunger guides.

3. In a match machine, the combination with the reciprocating plungers and the splint carrier, of guides for the plungers, and vertically adjustable brackets supporting 15 the guides.

4. In a match machine, the combination with the reciprocating plungers and the carrier for the splints, of a plate having one part formed into guides for the plungers, a 20 second part formed into guides for the

plungers and for the splints as they are delivered to the plungers, and means for simultaneously adjusting both guides.

5. In a match machine, the combination with the splint carrier and the reciprocating 25 plungers, of a guide for the plungers, a guide comb parallel with the first guide arranged to receive the plungers, the teeth of the guide comb being rounded on top, and a third set of guides adjacent to the carrier 30 and in alinement with the first two mentioned guides, the plunger guides, the guide comb and the splint guides being all connected together, and means for simultaneously adjusting the whole guide mechanism. 35
